2 Claims. (Cl. 220—15)

The present invention relates to refrigerators and more particularly to a closure structure between the outer shell and inner liner of a refrigerator cabinet.

Conventional refrigerator cabinets comprise an outer shell, an inner liner spaced inwardly from the shell and a body of insulation therebetween. The outer shell and inner liner are usually constructed of highly heat conductive sheet metal, such as steel, aluminum or the like, to provide the necessary strength and a breaker strip of a low heat conducting material is mounted between the shell and liner at the front of the refrigerator. The breaker strip provides a thermal barrier between the metal walls of the shell and liner at the outside and inside of the refrigerator and the breaker strip is usually constructed to provide an attractive trim strip and many times constitutes the door jam engaged by the gasket on the door.

Such breaker strips are usually attached by screws requiring considerable time and expense to apply and remove. Also considerable care must be used in the manufacture of the parts so that they properly fit each other to align the holes through which the fasteners are applied. Even though the parts are carefully manufactured, the breaker strip does not always tightly engage the shell and liner when the parts are assembled, due to warping of the parts or uneven strain applied to the breaker strip by the fasteners. However, even if properly applied, the breaker strip does not prevent moisture in the air at the outside of the refrigerator from flowing into the space between the shell and liner and condensing on the outside of the liner. Such condensate permeates the insulating material in the space and increases its thermal conductivity so that heat flows from the ambient to the interior of the refrigerator at a faster rate and increases the load on the refrigerating unit or, when the capacity of the unit is reached, increases the temperature in the refrigerator above desirable limits.

One of the objects of the present invention is to prevent the flow of moisture from the ambient to the insulating space between the outer shell and liner.

Another object is to provide a closure structure between the shell and liner of the refrigerator which acts as a moisture barrier between the ambient and insulation space as well as a thermal barrier between the shell and liner.

Another object is to provide a snap-on breaker strip which may be easily and quickly applied and yieldingly engages the outer shell and liner uniformly at all points throughout its length.

Another object is to provide a breaker strip construction which eliminates the necessity of fasteners and the necessity of aligning holes in the parts during assembly.

Still another object is to provide a combined breaker strip and moisture seal construction which is of simple and compact construction, adapted for economical manufacture and one which is reliable in operation.

These and other objects will become more apparent from the following description and drawings in which like

2

reference characters denote like parts throughout the several views. It is to be expressly understood, however, that the drawings are for the purpose of illustration only and are not a definition of the limits of the invention, reference being had for this purpose to the appended claims.

In the drawings:

Figure 1 is a perspective view of a refrigerator incorporating the novel features of the present invention;

Figure 2 is a sectional plan view taken on line 2—2 of Figure 1 to show the relationship of the combined breaker strip and seal to the outer shell, inner liner and door;

Figure 3 is an enlarged perspective view of a portion of the outer shell and liner illustrated in Figure 2 and showing the construction of the parts and the location of the seal strip therebetween;

Figure 4 is an enlarged sectional plan view taken on line 4—4 of Figure 1 and showing the initial position of a snap-on breaker strip section as it is about to be mounted;

Figure 5 is a view similar to Figure 4 showing the breaker strip section mounted in position on the refrigerator cabinet with each edge locked to the outer shell and inner liner, respectively;

Figure 6 is a front elevational view of a snap-on corner section of the breaker strip applied between vertical and horizontal sections to cover the corner; and

Figure 7 is a transverse sectional view taken on line 7—7 of Figure 6 to show the right angular front and side walls, the reduced feathered edge portion overlying the end portion of the vertical section and the locking lugs and spring clips on each right angular wall.

Referring to the drawings, the invention is shown applied to a refrigerator 10 having a refrigerated food storage compartment 11 closed by a door 12 and a machine compartment 13 below the refrigerated compartment having an access door 14. It will be understood, however, that the invention can be applied to other types of refrigerators, such as those having multiple doors or those having a refrigerating unit located at the rear of the refrigerated compartment.

The refrigerator 10 in the illustrated embodiment comprises an outer shell 15, an inner liner 16 spaced inwardly from the outer shell and insulating material 17 therebetween. The outer shell 15 and inner liner 16 may be of one piece construction or may be fabricated from a plurality of parts as illustrated. As shown in Figure 1, the outer shell comprises opposite side sections 18 and 19, a top section 20 and a stile section 21 between the refrigerated compartment 12 and machine compartment 13 therebelow. Similarly, the inner liner 16 comprises opposite side panels 22 and 23, a rear panel 24, a top panel (not shown) and a bottom panel 25, each joined to each other at their edges to form a box-like structure having an open front. Such a construction permits the use of side sections 18 and 19 with top and stile sections 20 and 21 of different lengths to provide refrigerators of different sizes.

The door 12 is hinged at the front of the side section 19 and has a latch 26 for engagement with a suitable latch keeper mounted on the side section 18. Door 12 is of the type described and claimed in my copending application Serial No. 737,275, filed May 9, 1958, and entitled Refrigerator Door Construction, and has a peripheral gasket 27 engaging the closure structure between the shell 15 and liner 16, constituting the subject matter of the present invention, to seal the refrigerated compartment 11 from the ambient.

In accordance with the present invention, a combined thermal barrier and vapor seal 30 is provided between the outer shell 15 and inner liner 16 at the front of the refrigerated compartment 11.

erator. The combined thermal barrier and vapor seal 39 comprises an inside vapor seal strip 31 and outside breaker strip 32 extending between the edges of the outer shell 15 and inner liner 16 around the entire periphery of the door opening. The invention also resides in part in the construction of the shell 15 and liner 16 for mounting the vapor seal strip 31 and breaker strip 32.

As shown in Figure 3 the side section 18 of the refrigerator cabinet 10 comprises a sheet metal plate such as, for example, aluminum forming a side panel. The forward edge portion of the plate is folded inwardly at right angles thereto to provide a front wall 33 with a rounded edge 34 therebetween and then rearwardly from the front wall 33 in generally parallel relationship to the side panel to form a flange 35. The plate is folded back on itself at the rearward edge of the flange 35 to strengthen the structure. Similarly, the opposite side section 19 and the top and stile sections 20 and 21 have front wall sections and rearward flanges forming a continuation of the front wall 33 and rearwardly extending flange 35 of the side section 18.

The forward edge of the side panel 22 of liner 16 terminates rearwardly from the front wall 33 of shell 16 and inwardly therefrom. An attaching strip 38 is mounted on the forward edge of the side panel 22 of liner 16 and extends throughout its height. As shown most clearly in Figure 3, the attaching strip 38 is a sheet metal piece having its forward edge portion 39 folded back on itself and overlying the opposite sides of the forward edge of the liner panel 22 and the terminal edge of the attaching strip forms a vertical locking shoulder 40 extending throughout the height of the liner panel 22. The folded edge portion 39 of the attaching strip 38 is permanently attached and sealed to the forward edge of the panel 22 as by welding it thereto. The rearward edge portion of the attaching strip 38 is folded laterally to provide a flange 41 projecting at right angles to panel 22. Cleats 42 are connected to attaching strip 38 at spaced intervals therealong. As shown most clearly in Figure 3, the cleats 42 are sheet metal stampings having a flat body portion and peripheral flange folded upwardly therefrom to provide a right angular end wall 43. End wall 43 of each cleat 42 is attached to flange 41 of attaching strip 38 by suitable fasteners 44, such as staples or the like. The forward edge of the other four panels of the liner 16 at the top, bottom and opposite side having attaching strips 38 and cleats 42 of similar construction around the entire periphery of the liner.

The ends of the flat body portion of cleats 42 opposite the end walls 43 overlie the rearwardly extending flange 35 of shell 15 and are attached thereto by suitable fasteners 45, such as screws, to mount the liner 16 in the shell. An attaching strip 46 of a construction similar to the attaching strip 38 is mounted on the side section 18 of shell 15 between the cleats 42 and flange 35. Attaching strip 46 has a flange 47 overlying the flange 35, an inwardly directed wall 48 forming a continuation of the front wall 33 of the shell 15 and a reversely folded end portion forming an outwardly projecting shoulder 49 at its terminal edge which extends throughout the height of the side section 18. As shown most clearly in Figure 4, the wall 48 of the attaching strip 46 overlies and is spaced forwardly from the flange 41 of the attaching strip 38 and its folded over edge terminates a short distance outwardly from the plane of the folded over edge 39 of attaching strip 38. Similar attaching strips 46 are provided on the corresponding flanges 35 at the top section 20, the opposite side section 19 and stile strip section 21 of the outer shell 15. Thus, the shell 15 has a marginal locking shoulder 49 extending around outer periphery of the open end of the liner 16 and the liner has a peripheral locking shoulder 49 at the rear of its terminal edge 39.

The vapor sealing strip 31 comprises a suitable fabric, such as cotton, impregnated with a thin coating of a resin, such as vinyl plastic, to render it moisture-proof while

retaining its flexibility. As shown in Figure 3, one edge of the vapor sealing strip 31 is clamped between the flanges 35 and 47 of the shell 15 and attaching strip 46 to form a vapor seal therebetween. Either or both sides of the strip 31 may have a pressure sensitive adhesive applied thereto, such as gum rubber or the like, to further improve the seal of the joint between the attaching strip 46 and flange 35 of the outer shell 15. The opposite edge of the sealing strip 31 is folded over the rearward side of the flange 41 of attaching strip 38 on liner 16 and against the outer face of the liner panel 22 and is attached thereto by a suitable pressure sensitive adhesive to provide a vapor seal with the outside of the liner. Similar sealing strip sections 31 are positioned between the outer shell 15 and inner liner 16 at the top, bottom and opposite side to form a complete seal between the shell and liner around the entire periphery of the door opening at the front of the refrigerator cabinet.

All of the other joints between the parts of the outer shell 15 and liner 16 also are sealed to prevent the flow of moisture into the space between the shell and liner. For example, the joints between the side sections 18 and 19 and the top and stile sections 20 and 21, and rear panel 50, see Figure 2, have a mastic therebetween. Openings 51 and 52 in the stile section 21 between the shell and liner through which the refrigerant lines extend from the evaporator to the refrigerating unit (not shown) and for the drain from the refrigerated compartment 11 have sealing sleeves 51 and 52 of rubber or the like. Thus, the space between the shell 15 and liner 16 is completely sealed to prevent moisture from flowing thereto from the ambient.

The breaker strip 32, shown in detail in Figures 2, 4 and 5, also is of novel construction and comprises sections adapted to be easily and quickly snapped in place to tightly and uniformly engage the shell 15 and liner 16. Each section of breaker strip 32 is of right angular form in cross-section having a front wall 55 and side wall 56. The breaker strip 32 is composed of any suitable insulating material of rigid type resilient plastic, such as a high impact resistant polystyrene, and the straight sections advantageously may be made as lengths of a one piece molded extrusion. As shown in Figures 2 and 5, the front and side walls 55 and 56 of the breaker strip 32 overlie the front and side of the attaching strips 46 and 38, respectively, and have longitudinally extending ribs or shoulders 57 and 58 extending throughout their length and in locking engagement with the shoulders 49 and 40 on the attaching strips 46 and 38 of the shell 15 and liner 16, respectively.

The front wall 55 overlies the front wall 48 of the attaching strip 46 and the adjacent portion of the front wall 33 of the shell 15 and the portion projecting outwardly from the shoulder 57 is curved inwardly and tapered to form a feathered edge 59 bearing against the front portion 33 of the refrigerator cabinet throughout its length. The side wall 56 bridges the space between the front wall 33 of the shell and forward edge of the liner 16. Side wall 56 has a rounded rearward edge 60 terminating in a flat face 61 extending rearwardly from shoulder 58 which bears against the wall 22 of the liner 16.

A flange 62 formed as an integral part of the breaker strip section projects laterally from the rearward face of the front wall 55 and constitutes a spring clip engaging the rearward side of the attaching strip 46 throughout its length to yieldingly retain the locking shoulder 57 in engagement with the locking shoulder 49. Spring clip 62 also acts to yieldingly engage the feather edge 59 with the front wall 33 uniformly throughout its length. Side wall 56 also has a flange 63 similar to flange 62 which engages the side of the liner panel 22 to yieldingly hold its locking shoulder 58 in locking engagement with a shoulder 40 and yieldingly hold the face 61 against the liner panel 22. Similar straight sections of the breaker

strip 32 are provided between the attaching strips 38 and 46 at the top, bottom and opposite side of the refrigerator cabinet.

Corner pieces 70, as shown in Figures 6 and 7 are provided for each corner of the breaker strip 32 between the adjacent vertical and horizontal straight sections. All of the corner pieces 70 are of identical construction and are adapted to be snapped into place in the same way as the straight sections. Each corner piece 70 has front plate portion 71 of right angular sections overlying the adjacent vertical and horizontal attaching strips 46 and a side wall plate portion 72 formed as an integral part thereof extending at right angles to the front plate portion 71 and having right angular sections overlying the adjacent vertical and horizontal sides of the attaching strips 38. The front and right angular side plates 71 and 72 have shoulders 73 and 74 at opposite ends adapted to align with the ends of the straight sections of the breaker strip 32 and thin sections 75 and 76 projecting laterally beyond the shoulders and overlying the ends of the straight sections. The thin sections 75 and 76 are of the same contour in cross-section as the end portions of the straight sections of the breaker strip 32 and are gradually tapered to provide a feather edge engaging the straight sections. The right angular sections 71 of the front plate have pins 77, one for each section, in locking engagement with shoulders 49 on the attaching strips 46 and a flange 78 engaging the opposite side of the attaching strip to yieldingly hold the pins in locking engagement. A single pin rather than a locking shoulder is required on the corner pieces to adapt them to be snapped into position. The sections of the side plate 72 each have a locking shoulder 79 for locking engagement with the shoulder 40 on the attaching strip 38 and a spring clip 80 projecting from the rear of the wall for yieldingly holding the shoulders in latching engagement. Thus, the straight sections and corner pieces of the breaker strip 32 close the opening between the outer shell 15 and inner liner 16 around the entire periphery of the door opening.

As shown in Figure 2, breaker strip 32 provides a thermal barrier of insulating material between the shell 15 and liner 16 around the entire periphery and also provides a decorative trim between the shell and liner. The front wall 55 also constitutes a door jamb for engagement by the gasket 27 on the door 12 to provide a seal between the ambient and the refrigerated compartment 11 to prevent air leakage therebetween. One form of the invention having now been described, the mode of operation and assembly of parts to form the combined moisture and thermal barrier 30 is explained below.

During the fabrication of the liner 19 and before it is assembled in the shell 15, the attaching strips 38 are mounted on the forward edges of the liner 16 by sliding the folder over edge portions 39 rearwardly onto the forward edge portions of the top, bottom and opposite sides of the liner and welding them thereto. Each of the attaching strips 38 extends through substantially the entire height or width of the panel of the liner 16 on which it is mounted. After the attaching strips 38 have been applied and welded to the forward edges of the liner 16, the end 43 of each of the spaced cleats 42 is attached to the flange 41 of the attaching strip as by stapling it thereto, see Figure 3. The rearward edge portions of the seal strips 31 having a pressure sensitive adhesive thereon are then pressed against the rearward face of each flange 41 and the adjacent outer side of the respective liner panel to adhere it thereto and form a moisture seal with the liner. Furthermore, the ends of the vertical and adjacent horizontal seal strip sections 31 are overlapped at the corners to complete the seal around the entire periphery of the open end of the liner. The liner is then in condition to be assembled with the other parts of the cabinet.

After a top section 20 and stile section 21 of proper width have been assembled between the side sections 18 and 19 to form the outer shell of a refrigerator cabinet,

the liner assembly 16 is mounted in the shell 15. This is accomplished by positioning the liner 16 in the shell 15 in the relative position illustrated in Figures 2 and 3. The forward edge portion of the seal strips 32 are then brought forward to overlie the flanges 35 at the opposite side sections 18 and 19 and the top and stile sections 20 and 21. Advantageously, the forward portions of the seal strips 31 also have a pressure sensitive adhesive applied thereto. The attaching strips 46 are then positioned to overlie the forward portions of the seal strips 31 between the flange 35 and cleats 42. Holes are then drilled through each cleat 42, the attaching strip 46 and flange 35 after which the self-tightening fastening screw 45 is applied through the drill hole to fasten the cleat to the shell. Thus, when all of the cleats have been attached to the attaching strip 46 of the shell 15, the liner 16 has been mounted in the shell 15 and the pressure of the spaced screws 45 on the flange 47 of the attaching strip 46 uniformly compresses the end of the sealing strip 31 uniformly along the flange 35 to seal the joint therebetween. As the sealing strip 31 is moisture-proof it seals the space between the shell 15 and liner 16 around the entire periphery of the cabinet.

The insulation 17 may have been placed at the inside 25 of the shell 15 prior to the assembly of the liner 16 therein or may be inserted through the back after the liner 16 has been assembled in the shell 15 and then closed by the back panel 50. Thus, the sealing strips 31 around the entire periphery of the door opening at 30 the front of the refrigerator cabinet and the sealing engagement of the other parts, such as the back panel 50 with the shell 15 and the sleeves 51 and 52 between the liner and outer shell prevents any moisture from entering the space between the liner and shell and thereby 35 eliminates the possibility of any water collecting in the space and affecting the properties of the insulation 17.

The straight sections of the breaker strip 32 are then snapped in place between the attaching strips 38 and 46. As shown in Figures 4 and 5, each breaker strip section 40 is pressed rearwardly from the position shown in Figure 4 to engage the rearward edge of wall 56 and spring clip flange 63 with the opposite sides of the folded over edge portion 39 of the attaching strip 38. Upon further rearward movement, the spring clip portion yields until the shoulder 58 on wall 56 snap over the shoulder 40 on the attaching strip 38. The spring clip flange 63 then presses the flat face 61 into engagement with the side of the liner panel 22 at the rear of the shoulder 40 uniformly throughout its length. Such rearward movement 50 of the side wall 56 of the breaker strip section aligns the front wall 55 with the front wall 33 of the refrigerator cabinet and inwardly projecting wall 48 of the attaching strip 46. The front section of the breaker strip 32 is then pressed outwardly to engage the front wall 55 and flange 62 with the opposite sides of the front wall 48 of the attaching strip 46 on the outer shell 15. Further lateral pressure of the breaker strip section 32 then causes the shoulder 57 to snap over the shoulder 49 on the outer shell 15 to lock the breaker strip section thereon. The yielding flange 62 then acts as a spring clip to yieldingly hold the shoulder 57 in locking engagement with the shoulder 49 and yieldingly engage the feathered edge 59 of the breaker strip section against the front wall portion 33 of the refrigerator cabinet. 60 The other sections of breaker strip 32 of the proper length are applied in a similar manner to the top section 20, stile section 21 and opposite side section 19.

Corner pieces 70 of the breaker strip 32 are then applied between the ends of adjacent vertical and horizontal sections by first pressing the rearward edge and 70 spring clips 80 on the right angular sections of the side wall 72 at the opposite sides of the vertical and horizontal end portions of the attaching strips 38 between the ends of the straight sections of breaker strip 32 until the spaced shoulders 79 snap over the shoulders 40; and

then pressing the right angular sections of the front wall 71 laterally to engage the spring finger clips 78 and pins 77 with opposite sides of front wall 48 of the attaching strip 46 and pressing it outwardly until the pins 77 snap over the shoulders 49. The spaced spring finger clips 78 then hold the pins 77 in locking engagement with the shoulders 49 and the reduced feathered edges in engagement with the adjacent end portions of the vertical and horizontal sections of the breaker strip 32. Thus, the breaker strip 32 extends around the entire periphery of the door opening and provides a thermal barrier between the shell 15 and liner 16. Furthermore, the face of the straight sections and the front wall 71 of the corner pieces 70 of the breaker strip 32 provide a continuous door jamb engaged by the peripheral gasket 27 on the door 12.

It will now be observed that the present invention provides a construction which prevents the flow of moisture from the ambient to the insulating space between the outer shell and liner. It also will be observed that the present invention provides a closure structure between the shell and liner of a refrigerator cabinet which acts as a moisture barrier between the ambient and insulating space as well as a thermal barrier between the shell and liner. It further will be observed that the present invention provides a novel form of breaker strip which may be easily and quickly applied and which, when applied, yieldingly engages the outer shell and liner uniformly at all points throughout its length. It will still further be observed that the present invention provides a combined moisture and thermal barrier which is of simple and compact construction adapted for economical manufacture and one which is reliable in operation.

While a single embodiment of the invention is herein illustrated and described, it will be understood that changes may be made in the construction and arrangement of parts without departing from the spirit or scope of the invention. Therefore, without limitation in this respect the invention is defined by the following claims.

We claim:

5 10 15 20 25 30 35 40

1. A refrigerator having a shell forming an outer wall and folded inwardly to form a front wall with a flange folded rearwardly from the front wall, a liner mounted in said shell in spaced relation thereto, an attaching strip on the shell having a flange overlying the rearwardly folded flange on the shell, a front wall aligned with the front wall of the shell and a folded over edge portion forming an outwardly projecting shoulder, an attaching strip on the liner having an edge portion folded over the forward edge of the liner to form an outwardly projecting shoulder on the liner and a laterally folded flange, a combined thermal and moisture barrier between the shell and liner comprising a breaker strip of heat insulating material extending between the shell and liner to provide the thermal barrier therebetween and a sealing strip of a moisture impervious material between the liner and shell at the rear of the breaker strip, one edge of the sealing strip being clamped between the shell and attaching strip and the other edge of the sealing strip being adhesively attached to the attaching strip on the liner, and said breaker strip having right-angular walls overlying the front wall of the shell and right-angular wall of the liner and having shoulders in locking engagement with the shoulders on one side of the attaching strips and spring clips engaging the opposite sides of the attaching strips to yieldingly hold the shoulders on the breaker strip in locked engagement with the shoulders on the attaching strips.

2. A refrigerator in accordance with claim 1 in which spaced cleats are attached to the flanges of the attaching strips on the shell and liner to mount the liner in the shell.
